Inventor:

G. G. Barry

UNITED STATES PATENT OFFICE.

GERALD G. BARRY, OF CHICAGO, ILLINOIS.

IGNITION TIMER.

Application filed January 17, 1925. Serial No. 3,028.

This invention relates to electric circuit makers and breakers, and particularly to that type known as "timers," employed in the ignition systems of internal combustion

5 engines. While the invention is susceptible if use in many other connections, it has been devised more particularly as an improvement in the electric ignition system used on the well known Ford automobile and tractor, 10 and will be described in that connection.

It is the purpose of my invention to provide a generally improved structure, which will simplify and reduce the cost of manufacturing, and at the same time furnish a 15 device which may be subjected to long, hard usage and be more efficient and dependable in operation than other devices for the purpose.

The invention consists in the details of 20 construction and arrangement and combination of parts to be hereinafter more fully described and particularly pointed out in the claims.

Referring to the accompanying drawings 25 forming part of this specification and in which similar letters or marks of reference designate like parts throughout the several figures:

Fig. 1 is a front plan view of the new 30 device, with the cover removed.

Fig. 2 is a vertical section view of the 35 stator element taken on the line 2—2 of Fig. 1, this view leaving out the central rotating member, but showing a dotted section outline of the removable cover.

Fig. 3 is a sectional detail view through the main metal track and supporting member taken on the line 3—3 of Fig. 1.

Fig. 4 is a sectional detail through the contacting brush assembly.

Fig. 5 illustrates contemplated modifications which may be made in the structure.

It is not deemed necessary to illustrate any 45 of the details of the associated engine parts.

As is quite well known, the Ford engine has 50 four spark plugs and coil units and a magneto or batteries associated therewith, and the timer, which determines the instant at which the spark plugs fire the explosive mixture in the respective cylinders is mounted on the engine housing in front of the timing gear case, this disc portion of the housing forming the base of the timer structure, and

the rotating element of the timer being secured upon and operated by the cam shaft, 55 which in turn is gear driven from the main engine shaft.

Referring to the drawings, a^1 is the main metal circular supporting band adapted to be seated in the customary circular recess 60 which is provided on the front of the timing gear case housing. Said circular recess on the engine housing is adapted to prevent eccentric displacement of the timer structure, and outward displacement is prevented by a 65 spring clamp pressing on the cover and secured to a stud or bolt on the wall of the engine housing. My structure is mounted and secured against displacement in the usual way, and this portion of the housing wall 70 serves as the base of the timer. The supporting band a^1 is preferably formed as an integral flange from a flat sheet metal blank a^2 , this blank having a series of four cut out portions a^3 , leaving four centrally directed flat portions, and the latter each have their extended ends bent inwardly as an integral flange, marked a^4 . The four flanges a^4 preferably do not extend to the housing, 75 but same are curved and arranged to form segmental parts or plates of the circular track for the traveling contacting member, as presently described.

Terminal contact plates c^1 alternate with these four track flanged plates formed on 85 the carrying member, the terminal contact plates being located at the cut out portions a^3 . These plates are also spaced from the housing, and it is necessary to insulate these terminals from the carrying member parts 90 a^1 , a^2 and a^4 . This may consist of a ring of hard fibre or other suitable insulating material extending all the way around and within the supporting band a^1 , the track plates a^4 and terminal plates c^1 being embedded in the insulating ring. However, I prefer to save the cost of much insulating material. In Fig. 1, I show the terminal plates c^1 carried on separate insulating blocks b^1 . A tubular insulating piece, marked b^2 , extends through the wall of band a^1 , to insulate the screw threaded stud c^2 of the terminal plate from said wall. This tubular piece or washer has a head b^3 on the outside to insulate the securing nuts c^3 , and same preferably extends into the block b^1 so

as to leave no parting in line with the wall a^1 to which current leakage might take place from the stud c^2 .

I may also form the insulation from one piece of fibre.

As already mentioned c^1 marks the terminal contact plates in the track surface, and c^2 the studs extending therefrom through the insulating elements. On the outside are shown two nuts for drawing the screw threaded stud and its terminal plate down to place and also to secure the customary leading-in wire. The terminal plates c^1 preferably have an integral flange, marked c^4 . The insulating blocks b^1 are shaped with a curve to conform to the wall a^1 and under surface of the plates c^1 ; the sides are straight and one side is tight against the flat under surface of what is shown left of the sheet a^2 at the cut out portions a^3 , and the opposite side and inner edge is flat against the flange c^4 on the respective terminal plate c^1 . It will be observed that in this way displacement of the insulating blocks and terminal plates is prevented after same are properly placed in position.

As illustrated in Fig. 1 and Fig. 2 there is thus made up a circular track surface comprised entirely of the metal terminal plates c^1 and track plates a^4 , open spaces being shown between these parts. With the roller type rotating circuit maker and breaker this cannot be used satisfactorily, but with the type of contacting brush which I show, and prefer, it can be. This brush is longer than and bridges across the intervening gap quite smoothly, without dropping into the air gap, as a traveling roller would. I thus save insulating material and also improve working conditions. Quite a space is afforded between the track and the outer wall a^1 in which oil, etc., which seeps into the structure may pass, the traveling brush simply forcing this off the track plates into the open spaces. There is no fibre or other insulating material forming any part of the track surface, which may become gummy under the dissolving attack of the oils, etc., and uneven wear on the fibre by the rotor travel, and which is the principal cause of timer trouble.

In Fig. 1 and Fig. 4 I illustrate a very simple, cheap and efficient rotor for successively making and breaking electrical ground connection with the respective plates c^1 . It is to be understood, of course, that the stationary element of the structure before described is adapted for use with other traveling contactor elements, whether of the roller or wipe contact types, although if a roller type is used it will be found better to provide suitable insulating material, rather than air space filling, between adjacent track surface plates. This may be like the modification illustrated in Fig. 5, where a larger

insulating block is shown, with a projecting portion, marked b^4 , forming a part of the smooth track surface on which the roller or brush may travel.

In my rotor illustrated in Fig. 1 and Fig. 4, d^1 denotes a tube or sleeve, which is mounted and detachably secured in the usual way upon the end of the cam shaft d^2 . An integral circular plate d^3 carries the outer details and serves to deflect any incoming oil, etc., which seeps in around the cam shaft, and aids in keeping same off the track surface. The plate d^3 may have a flange d^4 , which I prefer to have entirely around the outer edge, and this flange d^4 has an in-turned lip d^5 . At this point there is a hole in the flange wall, and the contacting brush d^6 is positioned here, projecting through the opening to come in contact with the surface of the track plates. The brush d^6 is normally held in this position between the lip d^5 and the back wall of plate d^3 by means of a flat spring d^7 . The brush has a straight slot d^8 opened in from one side and extending through the center of the body, as best shown in Fig. 4. The spring d^7 is preferably made from flat stock, bent to the circular shape shown and the two ends riveted or otherwise secured to the flanged wall d^4 as indicated at d^9 .

This brush is reversible. The tension of the spring holds same in outward engagement with the track surface. I prefer to make the track plates of steel and the brush of socalled "blendite" metal an anti-friction high speed bronze alloy. When the surface of the brush wears it may be forced back clear of the opening in the flange wall d^4 through which it projects, and then to one side, along the flat spring, so as to clear the extended lip d^5 . The brush may then be taken off the spring through the open sided slot d^8 and be reversed and returned to operating position.

In Fig. 1 the dotted outline e^1 indicates a suitable cover, and e^2 marks an indentation centrally of the outer portion to receive one end of the usual spring clamp for holding the timer structure in place against the engine housing. This cover is preferably made removable from the stator, so that the main rotor and stator parts can be mounted and examined and then the cover placed in position.

A lug f^1 is bent and may be riveted as indicated at f^2 to the top of the wall of band a^1 , as shown in Fig. 1 to receive the rod or other operating means to move the stator to advance or retard the spark.

Referring now to Fig. 5, there is illustrated some modification in detail which may be employed. As already mentioned, the space or gap between the adjacent terminal plates c^1 and track plates a^4 may be taken up with insulating material b^4 , where

such a track surface is desired. An insulating ring may fill the space between the track plates and flanged wall a^1 . However, there is no need of wasting insulation under the plates a^4 . To form the insulating members from separate fibre blocks not only saves the unnecessary part of the ring under plates a^4 , but as a matter of fact saves considerably more, due to the fact that such fibre rings 10 are formed from a flat sheet and the center is wasted by the necessary broaching operation. The forming operation on these separate insulating blocks will not occasion so much waste. A further improvement in operation and reduction in costs may be accomplished by reducing the relative size of the terminal plates c^1 , or space on the circular track surface taken up thereby, in comparison with the surface space of the plates a^4 . 20 This reduces the size of the insulation blocks required even where provided with the projections b^4 filling the gaps, and, of course, further reduces the insulating material under terminal plates c^1 if an insulating block 25 like the ones shown in Fig. 1 is employed.

A roller type contacting brush would be less satisfactory to use here for the further reason that, as the roller in traveling makes only a "line contact" it would provide a circuit connection only via the roller to the other parts of the rotor structure to the cam shaft, and the smaller terminal surface might not allow the moving "line contact" to be maintained long enough. I prefer to 35 employ a spring pressed wipe contact brush, the track face of which is long enough to extend across the small terminal plate c^1 from the track plate a^4 on one side to the plate a^4 on the other side, as shown by the 40 dotted outline. Thus it will be observed that as the brush approaches to close the circuit, the circuit is not only established via the brush to the cam shaft but there is really a better connection from the first plate a^4 45 via the brush as a bridge to the terminal c^1 , and as the brush travels on to the next adjacent plate a^4 such electrical connection is maintained until the other end of the brush leaves the terminal c^1 .

50 Those familiar with the manufacture and use of such timers will recognize the advantages of this invention and of its operation without any more detailed description. The low tension primary side of the four coils 55 usually employed are connected by wires leading to their proper respective terminal plates c^1 . As the rotor is driven around by the cam shaft, the circuit is successively closed with the respective terminal plates c^1 , 60 allowing current to flow to energize its connected coil and provide the high tension current which is led to the respective proper spark plugs, and the current flow through that coil ceases as the rotor breaks the circuit in passing off its terminal plate c^1 . 65

Various changes in detail may be made in the structure without departing from the spirit and scope of the invention as set forth in the claims, and I do not desire any undue limitation therein. Having described the invention in its preferred embodiment what I claim as new and desire to secure by Letters Patent is the following:

1. In a device of the character described, the combination of a metal supporting plate 75 having a circular band adapted to be mounted against a base, a supporting plate, a series of cut out portions in the supporting plate and integral with each of the series of plate surfaces left therebetween a flange curved 80 and arranged to form segmental parts of a track surface on which a rotor travels, a series of metal terminal contact plates likewise suitably curved and arranged to form parts of said track surface alternating with the 85 said track surfaces from the support member, separate insulating supporting blocks for each of said terminal contact plates, air gaps between the adjacent track surface plates, and rotating means for making and 90 breaking electrical connection between the terminal contact plates and the engine structure, substantially as set forth.

2. In a device of the character described, the combination of an annular band, a plate 95 having cut out portions and a series of inwardly projecting flanges, a series of terminal contact plates, alternating with the flange plates and with same arranged to form the circular track surface on which a 100 rotating distributor travels, and separate insulating material supporting pieces for each terminal contact plate.

3. In a device of the character described, the combination of a supporting plate having 105 an outer annular band adapted for mounting, and having cut out portions and a series of integral flanges, a series of metal terminal plates alternating with the said integral flanges on the supporting plate, the said 110 plate flanges and terminal plates being curved and arranged to form a circular track for the traveling rotor member, and insulation for normally electrically separating the terminal plates from the balance of the 115 structure.

4. In a device of the character described, a rotor member comprising a sleeve, an integral circular plate having a flange thereon and an opening in the said flange wall, 120 an inturned lip on the said flange wall adjacent said opening, contacting brush, a straight open sided slot through the center of said brush, a flat spring in said slot, and means for securing said spring to the flange at the opposite edge of the circular plate, substantially as shown and described. 125

5. In a device of the character described, a supporting member formed from a metal plate, having a flange at its outer edge, in- 130

wardly directed and adapted for mounting against a suitable base, a series of portions cut out from the center of the plate and from each of the centrally directed portions of the plate left remaining an integral flange also directed toward the base, a series of terminal contact plates, alternating with the flanges on the said supporting plate member, insulation in which the terminal contact plates are supported, and the entire series of alternating integral flanges and terminal contact plates suitably curved and arranged to form a track surface on which a circuit make and break member travels.

15 6. In a device of the character described, the combination of a metal supporting plate having a circular mounting band, the said supporting plate having a series of cut out portions and integral with each of the series 20 of plate surfaces left therebetween, a flange curved and arranged to form segmental parts of a track surface on which a rotor travels, a series of metal terminal contact plates alternating with the said flanged track surfaces from the support member, insulation for said terminal contact plates, and rotating means for making and breaking electri-

cal connection with the terminal contact plates substantially as set forth.

7. In a device of the character described, 30 the combination of a plate having an outer annular mounting band, portions eliminated from the center of the plate, a series of integral inwardly projecting flanges, a series of terminal contact plates, alternating with the 35 said flange plates and the two series of plates arranged to form a circular track surface on which the rotating member travels, and insulating material for electrically separating the terminal contact plates from each 40 other and the balance of the structure.

8. In a device of the character described, the combination of a supporting plate member, having cut out portions and a series of inwardly projecting flanges, a series of terminal contact plates, alternating with the flange plates and with same arranged to 45 form a circular track on which a rotating distributor is adapted to travel, and insulating material in which the terminal contact 50 plates are supported.

In testimony whereof, I have hereunto signed my name to this specification.

GERALD G. BARRY.
